UNITED STATES PATENT OFFICE.

CARL A. PFANSTIEHL, OF HIGHLAND PARK, ILLINOIS, ASSIGNOR TO PFANSTIEHL COMPANY, INC., OF NORTH CHICAGO, ILLINOIS, A CORPORATION OF NEW YORK.

LABORATORY-FURNACE.

1,283,285.

Specification of Letters Patent.

Patented Oct. 29, 1918.

Application filed July 17, 1916. Serial No. 109,863.

To all whom it may concern:

Be it known that I, CARL A. PFANSTIEHL, a citizen of the United States, and a resident of Highland Park, in the county of Lake 5 and State of Illinois, have invented certain new and useful Improvements in Laboratory-Furnaces, of which the following is a clear, concise, and exact description, reference being had to the accompanying drawings, forming a part of the specification.

My invention relates to an electric furnace equipped with heating, cooling, electrical and mechanical devices, so that the furnace may be used for a large variety of purposes 15 to meet the requirements of an experimental or development laboratory. Many features of my invention are also of utility in the manufacture of chemicals or compositions of matter in a commercial way, though it is 20 unnecessary that all of the features of my invention be incorporated in a commercial embodiment designed for the accomplishment of one specific end or the manufacture of one specific substance.

25 The objects of my invention are the provision of a furnace which may be readily and quickly opened and closed, and which, without the loss of time or the exertion of great effort on the part of the operator, becomes perfectly sealed against the passage 30 of atmosphere to or from the furnace when the furnace is closed; the provision of perfectly sealed joints for leading in electrical conductors and movable shafts; the provision 35 of a suitable electrically heated crucible; the provision of water cooled and adjustable supports for the heating element, and the provision of suitable supporting and controlling mechanism for the furnace and its 40 cover. Another object of the invention is the provision of one or more observation windows and particularly the means provided for preventing breakage of the glass by heat, and for sealing around the glass to 45 prevent the passage of air or gas.

Still further features of the invention will be pointed out in the following detailed description and claims.

50 My invention is illustrated in the accompanying drawings, in which—

Figure 1 is an elevation of the furnace and supporting frame;

Fig. 2 is a plan of the furnace and its supporting frame;

55 Fig. 3 is a vertical section through the furnace taken on the line 3—3 of Fig. 2;

Fig. 4 is a plan view of the furnace with cover removed;

Fig. 5 is a section through one of the side observation windows;

Fig. 6 is a detailed sectional view of the mechanism for leading in electrical conductors or binding posts;

Fig. 7 is a detailed sectional view of the mechanism for leading in rotatable or oscillating shafts; and

Fig. 8 is a section taken on the line 8—8 of Fig. 3, and showing the structure of the movable heating element support.

I preferably support my furnace upon a 70 platform 1, mounted in a suitable manner upon rollers or casters 2. Extending vertically from the platform 1 are six uprights 4 preferably of pipe. These uprights are united at their upper ends by means of pipe 75 sections 5 and couplings 6, so as to form a rigid structure for the support of the furnace cover lifting and adjusting mechanism. This lifting and adjusting mechanism is preferably in the form of a windlass provided with two short drums 8 and 9, to which a pair of cables 10 are attached, the latter passing over suitably supported pulleys 11 and 12 and being attached at the other end to the furnace cover 13.

The base 14 of the furnace is held at a convenient height above the platform 1 by means of a pair of columns 15, these columns being rigidly attached both to the base 14 and to the platform 1. This base 90 member 14 shown in section in Fig. 3 comprises upper and lower walls and a plurality of spacing webs 16, by means of which a chamber is provided for the circulation of water or other cooling substance. The spacing web 16 as illustrated in Fig. 4 extends only partially across the base member, thus facilitating the circulation of the cooling fluid which enters and escapes from the base chamber through the lead-in and exhaust 100 pipes 19 and 20.

Around the periphery of the furnace base 14 is a channel 21, the base of which is provided with a pair of circumferential ridges 22, the apexes of which are comparatively 105 sharp so as to press themselves into the circumferential rubber or fiber gasket 23 which is carried upon the lower face of the walls of the furnace cover 13. The channel 21 contains mercury, oil, or some other suitable 110 sealing fluid which normally stands at such a level as to be slightly above the apexes of

the ridges 22. When the cover 13 is brought into place the sealing fluid rises slightly around the cover, thus eliminating any possibility of the passage of air through the pores of the rubber or fiber gasket 23.

In order that the positioning of the operating parts of the furnace shall not be affected by the removal of the cover 13, all conducting or operating devices for the manipulation of the furnace are preferably led in through the base member 14. This is true of the main electrical terminals 25 and 26. It has been found impracticable to produce an absolutely non-leaking insulating joint between electrical conductors and the furnace walls without the aid of oil or some other sealing fluid. In accordance with my invention there is provided an oil pan 30 which is attached to and extends beneath the furnace base 14, and which is adapted to contain oil to a level above the external openings in the base 14 through which the conductors 25 and 26 extend. This pan is attached to the furnace base 14 by any suitable means such as soldering.

Each of the conductors 25 and 26 is provided with a water circulating duct 31 through which water is caused to flow by forced feed to prevent an abnormal rise in temperature of the electrodes or heating element supports. The electrode support 26 is provided with a bridge member 33 through which a set screw 34 extends for clamping the conducting lock 35 upon the heating element or other device which is to be supported between the terminals 25 and 26. In order that the expansion and contraction of the heated element will be taken up the electric terminal 25 is provided with a sliding member 37 which fits upon the horizontal portion of the terminal 25 with a dove tail connection, as shown in Fig. 8. The parts 25 and 37 are preferably made of copper and the contacting surfaces between these parts are made large so that the heat will be quickly conducted away from the movable portion 37 by the cooler portion 25. In view of the fact that very heavy currents are sometimes used in my furnace I do not depend upon the contact between the elements 25 and 37 for the electric circuit, but provide flexible conductors 38, so arranged as to offer very slight resistance to the movement of the member 37 upon the member 25. These conductors are clamped in good electrical connection with the members 25 and 37, and may also, if desired, be soldered thereto to decrease the contact resistance. A small spring 40 is provided so that a heating element may be supported between the electrical terminals merely by the end pressure exerted by the spring 40 on the movable terminal 37. This expedient is resorted to in sintering ingots of compressed metal by use of the current for the reason that the in-

got in being sintered materially contracts, thus making necessary the automatic follow-up movement of the terminal 37.

The furnace cover 13 is constructed with inner and outer walls, the space between being filled with water or other cooling fluid which is kept in circulation by a forced feed of liquid through the intake and exhaust pipes 42 and 43. Extending axially above the center of the cover is a projection 44, 75 which supports an observation window 45. This window, which is preferably of glass, is clamped by means of screws 46 against two soft gaskets 47 and 48. These gaskets are so positioned as to provide an annular 80 space between them which is preferably filled with mercury to form a seal which is impenetrable by air or gases. By positioning the window 45 at some distance above the heated element of the furnace and at the extremity of a chamber which is thoroughly water cooled by water circulated through the intake and exhaust pipes 49 and 49', I am able to eliminate the breakage of the glass even though the temperature of the 90 heated element is raised to several thousand degrees Fahrenheit. I preferably provide other observation windows such as shown in Fig. 5 at one or more points through the vertical walls of the cover. 95 The structure of these windows is the same as described for the window 45, excepting that I preferably provide a duct 50 through which to fill the mercury chamber 51 after the glass has been secured in place. 100

I have herein illustrated one of the specific devices for which my electric furnace is designed. This device is a carbon heating element 53, the central portion of which is cupped out to form a receptacle in which a 105 crucible of platinum or porcelain may be placed for heating or in which such substances as are non-conductors when hot may be directly heated. I have found it preferable to neck the carbon element 53 adjacent the cupped portion so as to concentrate the greatest heating effect at the receptacle. The method of necking is illustrated at 54 in Fig. 3.

In order that my furnace may be used for 115 a great variety of purposes and in order that a plurality of electric circuits may be provided by means of which various electrically controlled devices may be operated within the furnace I provide a plurality of conducting elements 56 which extend through apertures in the base of the furnace and to which conductors may be attached both outside and within the furnace chamber. Each of these electric leads is insulated and sealed 120 as illustrated in Fig. 6. The conductor 58 is surrounded within the base portion by cement 59, which is poured in place about the conductor after the nuts 60 have been clamped upon the insulating washers 61. In 130

order to make a perfect seal a cup 62 containing oil is threaded upon the lower end of the conductor 58.

It sometimes becomes necessary to stir, fan, saw or perform some other mechanical operation upon some part which is being threaded within the furnace chamber. To facilitate such mechanical operations as may be desired I provide a plurality of rotatable shafts 63, which extend through the base portion and which are provided with gears and pulleys to facilitate the application of power thereto. The method of carrying these rotatable shafts through the base member is illustrated in Fig. 7. In this figure it will be seen that the block 65 constitutes the principal bearing for the shaft 63. A shoulder 66 on this block is clamped against the underside of the base by means of the nut 67, the same type of mercury seal being provided for this block as for the observation windows. The block 65 is provided at its external end with a chamber 68 for the reception of mercury which is confined by means of the threaded plug 69 and the rubber washers 70. The inner end of the plug 65 is provided with a similar but somewhat smaller aperture 72, which contains a piece of oily felt, the oil serving to preserve the lubrication of the shaft. Carried upon the shaft and rotatable therewith is a cup 73 for the reception of mercury to a level above the joints between the plug 69 and the sleeve 65.

In order that water, gases or other fluids may be carried into and out of the chamber of the furnace during its operation I provide a number of tubular connections 75 which may be used in an obvious manner for the purposes above described.

From the foregoing detailed description it will be seen that my furnace is capable of a great variety of uses, for example, it may be used as a reducing furnace by providing a suitable hydrogen atmosphere for bringing about the chemical reduction of an oxid; it may be used as a sintering furnace by passing a heavy current through an ingot of compressed metal in the presence of hydrogen or in a vacuum or rarefied atmosphere as may be required; it may be used for quantitative analysis where it is desired to determine accurately the quantity of oxygen, hydrogen or other gas which unites with some other gas or chemical under the influence of heat; it may be used for bringing about the weld or union of metals which do not readily unite in the presence of air even when heated to their melting point; it may be used for making compounds of metals which have to be mechanically stirred at very high temperatures. In fact, it may be used for almost any purpose in which materials are to be acted upon or observed at high temperatures.

Although my invention is herein described with reference to the details of a specific embodiment thereof it is to be understood that many of these may be varied or entirely omitted without departing from the spirit or scope of the invention.

What I claim as new and desire to secure by Letters Patent of the United States, is:

1. A laboratory device comprising a substantially horizontal base member having a groove in its upper surface, a hollow cover member adapted to fit within the groove in the surface of the base member, sealing fluid within the groove, a water jacket for the cover member, and flexible intake and exhaust pipes for the water jacket whereby the cover member may be raised and lowered from the base member without interrupting the circulation of water through the water jacket.

2. In a laboratory device the combination with a substantially horizontal base member of a hollow cover member, a frame within which said cover member is located, means carried by said frame for lifting the cover member from the base member, intake and exhaust ports extending through the base member whereby gas or other fluid may be introduced into the inclosure and withdrawn therefrom through permanently fixed piping.

3. In a laboratory apparatus the combination with a base member of a water jacket therefor, a pair of electrical terminals extending above the base member and having openings therein for the circulation of cooling fluid, hollow electric conductors extending through the base member, and a pan beneath the base member and containing a non-conducting sealing fluid to prevent leakage by the electric conductors where they pass through the base member, and a cover for the base member inclosing said electrical terminals.

4. A laboratory apparatus comprising a base member, a cooling jacket therefor, electrical conductors extending through the base member and having terminal portions above and below said base member, and a cup carried by each of said conductors and adapted to contain an insulating sealing fluid for preventing the passage of gas by the conductor where it passes through the base member, and a box-like cover member providing a chamber above the base member.

5. In an electric furnace the combination with a base member of an electrically heated element carried thereby, a cover member having water jacketed sides and top, an observation window through the top of the cover member, said window being displaced above the top of the cover member, and a water jacketed carrier extending between the window and the top of the cover member whereby the glass of the window is protected from

the extreme heat of the furnace by a column of water cooled gas.

6. An observation window for electric furnaces comprising a transparent member, 5 means to clamp the transparent member against the body of the furnace, a duct in the body of the furnace and sealing fluid in the duct whereby gas is prevented from passing between the body of the furnace and the 10 transparent member.

7. An observation window for high temperature furnaces from which oxygen is to be excluded during the operation of the furnace comprising a plate of transparent material, a pair of concentric yielding gaskets between the furnace body and the transparent material, said gaskets being so placed as to form a duct between them, a sealing fluid in said duct, and means to hold the 20 transparent material firmly against said gaskets.

8. A laboratory device comprising a base member and a box-like cover, a channel in the base member into which the lower edge 25 of the box-like cover extends, a sharp topped continuous ridge carried by the base member, a yielding gasket carried by the cover member and adapted to engage the sharp topped ridge of the base member, and sealing fluid within the channel of the base member and entirely covering the point of contact between the cover member gasket and the ridge of the base member.

9. A laboratory device comprising a base 35 member and a box-like cover member, a channel in the base member, a knife-edge carried by one of said members and being continuous throughout the point of union between the base member and the cover 40 member and a yielding gasket carried by the other of said members and also being continuous throughout the point of union of the base member and the cover member, said gasket and said knife-edge being brought together when the cover is in place, and a sealing 45 fluid within the channel in the base member and continuously engaging the point of contact of said knife-edge with said gasket.

50 10. A laboratory device comprising a base member and a removable cover member, a

rotatable shaft extending through the base member, a sleeve surrounding said shaft, a chamber within said sleeve and surrounding said shaft, sealing fluid in said chamber, and 55 a flexible gasket for preventing the sealing fluid from passing along the shaft from said chamber.

11. A laboratory device comprising a base member and a removable cover member, a 60 rotatable shaft extending through the base member, a sleeve surrounding said shaft, a chamber within said sleeve and surrounding said shaft, sealing fluid in said chamber, a 65 flexible gasket for preventing the sealing fluid from passing along the shaft from said chamber, a collar in said sleeve, an annular chamber in said collar, and sealing fluid in said chamber to prevent the passage of gas between the base member and the 70 sleeve.

12. In an electric furnace the combination with a pair of terminals of a resistance element extending horizontally between said terminals, a cup in said resistance element, 75 and a neck in the heating element adjacent each side of said cup whereby the heating effect of the element will be concentrated in the cup, one of said terminals having a horizontal sliding movement whereby the heating element may expand and contract without placing it under undue strain and without affecting the electrical connection therewith.

13. A laboratory device comprising a base 85 and removable cover, electrical conductors extending through said base, a rotatable shaft extending through said base, intake and exhaust pipes to conduct gases to and from the hollow portion of the device, and 90 sealing fluid surrounding all of the joints of said device excepting those which are soldered whereby the device may be permitted to stand for long periods without danger of the escape of inclosed gas or the entrance of 95 atmosphere.

In witness whereof, I hereunto subscribe my name this 13 day of July, A. D. 1916.

CARL A. PFANSTIEHL.
